(57) **CLAIM**

I claim the ornamental design for the tractor loader backhoe with rotatable cab, as shown.

DESCRIPTION

FIG. 1 is a perspective view of the tractor loader backhoe with rotatable cab showing my new design;

FIG. 2 is a right side view thereof;

FIG. 3 is a top plan view thereof;

FIG. 4 is a front view thereof;

FIG. 5 is a left side view thereof;

FIG. 6 is a bottom plan view thereof; and,

FIG. 7 is a rear view thereof.

1 Claim, 7 Drawing Sheets
